Brooklyn, N. Y.

Application May 15, 1940, Serial No. 335,232

1 Claim. (Cl. 40—126)

This invention relates to match packages and the like and more particularly to the type of match packages commonly referred to as a match book.

The principal object of the invention is to provide a novel type of package or match book wherein provision is made for increasing the appeal and for stimulating the curiosity as to the nature of certain advertising or printed matter appearing on the matches or the cover.

A further object is to provide an advertising novelty by incorporating in the cover of the match book a design which is completed by some or all of the matches.

Another object of the invention is to provide a match book having a design cut-out in the cover or covers thereof to illustrate the advertising matter printed thereon.

Still a further object is to provide a match book or match package having a transparent window in the cover or covers thereof in the form of a design and through which window the matches are visible.

Other objects and advantages inherent in the invention will become apparent as the specification proceeds and when taken in conjunction with the accompanying drawing which illustrates a preferred embodiment thereof.

In the drawing:

Fig. 1 is a front elevation of the match book with a portion cut away and which match book has a window in the form of a design which is completed by the matches visible therethrough.

Fig. 2 is a section along the line 2—2 of Fig. 1, and

Fig. 3 is a perspective view of a modification.

Referring more particularly to the drawing, the match book includes a usual comb-like section indicated at 10. The matches are enclosed in a covering strip composed of any suitable flexible material, such as cardboard or the like. The covering strip is folded about the matches to form an integral back wall 11, a front flap 12

and an upturned flap 13 for retaining the front flap 12. The upturned flap 13 is covered with abrasive material against which the matches may be ignited in the usual manner. A staple or other equivalent fastening element 14 extends through the retaining flap 13, through the lower end portion of the match comb and through the back wall of the covering strip.

Advertising matter may be printed on the front flap 12 as well as on the back wall 11. As shown in Fig. 1, greater emphasis may be given to the advertisement by cutting out in the cover strip the design of a smiling mouth in which the matches constitute the teeth.

The cut-out design is preferably backed by a transparent film 15, such as "Cellophane."

Fig. 3 shows a match book having a different design cut-out therein to illustrate a different advertisement. It will be understood that the ornamental appearance of the design may be enhanced by coloring all or some of the matches visible through the cut-out design.

It will be understood that the invention is susceptible of expression in a variety of ways within the scope of the following claim.

We claim:

A match book or the like, comprising a match comb consisting of a plurality of matches situated one next to the other and having interengaging edges, and a covering folded to form a front flap covering said match comb, advertising matter printed on said front flap, a design so selected that it illustrates said advertising matter and having a portion printed on said front flap, another portion of said design being formed by a cut-out portion of said front flap, the edges of the matches showing through said cut-out portion forming a third portion of said design, said design being completed by all of said three design portions.
